(57) CLAIM

The ornamental design for a camper trailer, as shown and described.

DESCRIPTION

FIG. 1 is a perspective view of a camper trailer, showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof; and,

FIG. 9 is an enlarged view of portion 9 shown in FIG. 2.

The broken lines showing of the camper trailer is for the purpose of illustrating the article and forms no part of the claimed design.

1 Claim, 9 Drawing Sheets
